UNITED STATES PATENT OFFICE.

JOSEPH E. LANDERS, OF NEW BEDFORD, MASSACHUSETTS.

INCLOSING CASE FOR ERASIVE RUBBERS.

SPECIFICATION forming part of Letters Patent No. 556,681, dated March 17, 1896.

Application filed November 9, 1895. Serial No. 568,407. (No model.)

To all whom it may concern:

Be it known that I, JOSEPH E. LANDERS, of New Bedford, county of Bristol, State of Massachusetts, have invented an Improvement in Inclosing Cases for Erasive Rubbers, of which the following description, in connection with the accompanying drawings, is a specification, like letters on the drawings representing like parts.

10 Many persons engaged in business find it desirable to carry always with them an erasive rubber, but such a rubber after having been carried in the pocket for any considerable period of time becomes soiled and coated to 15 such an extent as renders it very undesirable for use.

The object of this invention is to provide a suitable casing for such a rubber whereby the latter may be carried in the pocket without 20 injury or soiling, yet may be conveniently and readily exposed when needed for use.

In the preferred embodiment of my invention I so construct the case that the moving parts shall rotate about a common axis, which 25 axis shall also be substantially coincident with that of a preferably circular or disk-like rubber.

In the drawings, Figure 1 in vertical section shows an inclosing case embodying my 30 invention, the rubber, however, being in elevation; Fig. 2, a similar view with the rubber exposed; Fig. 3, an edge view of Fig. 1; and Fig. 4, a vertical section on the dotted line $x-x$, Fig. 1.

35 In the embodiment of my invention selected for illustration herein and shown in the drawings the inclosing case A comprises a plurality of parts a a' , shown as two in number, but which may be of any desired number, 40 if desired. The two parts a a' are each semi-cylindrical in shape, one fitted and adapted to telescope within the other, the two parts being preferably connected by a pivot a^2 . The smaller part, a' , is shown as provided at 45 one end with an outturned lip a^3 adapted to engage the hooked end a^4 of a spring-tongue a^5 , formed integrally with the part a . At its end opposite the lip a^3 the part a' is provided with another outturned lip a^6 , between which

and an inturned lip a^7 on the part a I have interposed a suitable, preferably spiral, spring s .

The rubber b (shown as circular in shape) is mounted in suitable manner also upon the pivot a^2 , about which it may be rotated to expose one or another portion of its surface.

50 When not needed for use the rubber is concealed by drawing the part a over into its position Fig. 1 and locking the same by engagement of its lip a^3 with the hooked locking-tongue a^4 , in which condition the case and 55 rubber may be readily carried in the vest-pocket without danger of soiling or injuring the rubber in the case.

When needed for use, the locking-tongue a^5 may be moved into its dotted position, Fig. 1, 60 by the fingers of the hand holding the case, when the spring s will automatically throw the cover or smaller part, a' , about its pivot in the direction of arrow, Fig. 1, partially, or it may be entirely, exposing one-half of the 65 rubber, in which condition the latter may be used for erasive purposes. It will thus be seen that the case is automatically opened at least sufficiently to expose a part of the erasive surface, and is locked in closing position 70 to prevent possible exposure of the rubber when carried in the pocket.

75 My invention is not limited to the particular embodiment herein shown.

Having described my invention, what I claim as new, and desire to secure by Letters Patent, is—

1. The herein-described inclosing case for rubbers and the like, the same consisting of a plurality of rotatably-connected and telescoping members, a locking device for locking the same in closed position, and means to automatically open the said members upon release of said locking device, substantially as described.

2. The herein-described inclosing case for rubbers and the like, the same consisting of a plurality of rotatably-connected and telescoping members, a locking device for locking the same in closed position, a spring interposed between the said members, and tending constantly to move to open the same, substantially as described.

3. The herein-described inclosing case for
erasive rubbers and the like, the same con-
sisting of the semicircular members pivotally
connected and telescoping one within another,
5 a spring interposed between lips on the said
members, and tending to open the latter, a
locking-tongue on one member and a co-op-
erating lip on the other, all operating, sub-
stantially as described.

In testimony whereof I have signed my name to this specification in the presence of two subscribing witnesses.

JOSEPH E. LANDERS.
